UNITED STATES PATENT OFFICE

HENRY J. DAVIES, OF BROOKLYN, NEW YORK.

DESIGN FOR COMBINED CLOCK AND MIRROR FRAME.

Specification forming part of Design No. **8,019**, dated January 26, 1875; application filed November 25, 1874
[Term of Patent 3½ years.]

To all whom it may concern:

Be it known that I, HENRY J. DAVIES, of Brooklyn, in the county of Kings and State of New York, have invented a new and ornamental Design for a Combined Clock and Mirror Frame, of which the following is a full, true, and exact description:

The nature of my design is fully represented in the accompanying drawing, in which—

Figure 1 is a perspective view of said design; Fig. 2, a sectional profile view on the line *x x*; Fig. 3, a similar view on the line *y y*; and Fig. 4, a profile view of the base portion of the frame.

The base is of circular form, with a border or edge molding, *b*, as shown in the profile view, Fig. 4. Mounted on this base, back of its center, is a flat standard or clock-carrying upright, *B*, having straight parallel sides, *c c*, for a certain distance from the base, and which portion is faced to form a rectangular mirror frame, *C*, the borders of which consist of an

ornamental molding, *d*, as shown in profile, Fig. 3. The straight sides *c c* of the standard *B* terminate above the mirror-frame in partially circular projections, *e e*, faced by circular moldings or protuberances, *f f*, the profile of which is shown in Fig. 2. The partially-circular projections *e e* connect at their inner and upper ends by gentle curves or sweeps, *g g*, with the upper portion, *h*, of the flat standard, which portion, *h*, is of circular contour.

I claim as my invention—

The design for a clock and mirror frame, consisting of the base *A*, standard or upright *B*, for carrying the clock, and the mirror-frame *C*, having the ornamental molding *d*, all substantially as described and shown in the accompanying drawing.

HENRY J. DAVIES.
